GAS COMPRESSOR

Aubrey C. Whiles, Mount Helix, Calavo Gardens, Calif., assignor of forty-nine per cent to Virgil Scott, Mount Helix, Calavo Gardens, Calif.

Application September 13, 1937, Serial No. 163,633

10 Claims. (Cl. 230—181)

My invention relates to a gas compressor; and the objects of my invention are:

First, to provide a gas compressor which is compact relative to its capacity to deliver compressed gas;

Second, to provide a gas compressor which delivers the compressed gas at a relatively high pressure;

Third, to provide a gas compressor which delivers a relatively steady flow of compressed gas;

Fourth, to provide a multistage gas compressor having a gas receiver intermediate its stages of compression; and

Fifth, to provide a gas compressor which is simple of construction and operation with respect to its purpose, durable, efficient, and which will not readily deteriorate or get out of order.

With these and other objects in view as will appear hereinafter, my invention consists of certain novel features of construction, combination, and arrangement of parts and portions as will be hereinafter described in detail and particularly set forth in the appended claims, reference being had to the accompanying drawings and to the characters of reference thereon which form a part of this application in which:

Figure 1 is a sectional view along the line 1—1 of Fig. 2 showing parts and portions in elevation to facilitate the illustration; Fig. 2 is a plan view 30 taken along the line 2—2 of Fig. 1 to show the cylinder arrangement and is of the same scale as Figs. 1 and 4; Fig. 3 is an enlarged scale sectional view along line 3—3 of Fig. 2 through the cylinder head 4d on the high pressure cylinder 4 showing particularly the valve arrangement therein and showing cylinder 4 fragmentarily; Fig. 4 is a sectional view taken along line 4—4 of Fig. 1 and is of the same scale as Fig. 1 and shows particularly the crankshaft and connecting rods; Fig. 5 is a 40 sectional view of the intermediate gas receiver only on an enlarged scale along the line 5—5 of Fig. 1; Fig. 6 is a fragmentary sectional view along the line 6—6 of Fig. 5 and on the same scale as Fig. 5 showing parts and portions in elevation to facilitate the illustration, and showing particularly the valve arrangement in said gas receiver; Fig. 7 is a sectional view taken along line 7—7 of Fig. 6 of the same scale as Figures 5 and 6, to show the low pressure cylinder inlet valve guide 50 and valve port, and how said guide is secured within said port; Fig. 8 is a sectional view along line 8—8 of Fig. 7 further disclosing how said valve guide is secured within said valve port; Fig. 9 is a partial sectional view along line 9—9 55 of Fig. 10 of the gas compressor in its modified

form, is of the same scale as Fig. 1, and shows particularly how the pistons for the high compression cylinders are geared to the piston for the low pressure cylinder; Fig. 10 is a top or plan view of the modified form of the gas compressor 5 along line 10—10 of Fig. 9 to show the cylinder arrangement and is of the same scale as Fig. 9; and Fig. 11 is a fragmentary sectional view taken through the line 11—11 of Fig. 9 showing particularly how the crankshaft for each high pressure 10 cylinder is supported and how the gear which meshes with the gear for the piston of the low pressure cylinder is secured thereon.

The subject matter of this application is disclosed in part in my application, Serial No. 54,682, 15 filed Dec. 16, 1935.

Similar characters of reference refer to similar parts and portions throughout the several views of the drawings:

The crankshaft casing and cylinder support 20 member 1, the crankshaft casing cover plate 2, low pressure cylinder 3, high pressure cylinders 4, 5, 6, and 7, intermediate gas receiver 8, crankshaft 9, low pressure cylinder inlet valve 10, and intermediate gas receiver inlet valves 11, 12, 13, 25 14 constitute the principal parts and portions of my gas compressor.

The crankshaft casing and cylinder support member 1 is substantially box shaped in its outward dimensions as will be seen from Figures 2 30 and 4, excepting that in its cross section, as seen best in Fig. 1, it is six sided with its bottom side being formed by the removable crankshaft casing bottom cover plate 2, said cover plate being secured to the member 1 by means of bolts 1a, 35 and its two removable longitudinal side plates 1g, the two ends and the top sides 1b, 1c, and 1d being in one integral member. Rigidly secured at its lower end to the upper side, 1b, of crankcase member 1 and extending upwardly therefrom, the 40 low pressure cylinder 3 stands vertically, and is centrally positioned with respect to said member 1, all as seen best in Figures 1, 2, and 4. Positioned about and equidistant from cylinder 3 are four high pressure cylinders 4, 5, 6, and 7. Said 45 high pressure cylinders are not vertically disposed with respect to base member 1, as is cylinder 3, but stand at an acute angle to the vertical. Cylinder 4 is correlated to 5 as is 6 to 7 as will be hereinafter described. For the particular structure shown the angle between the axes of cylinders 4 and 5 and the axes of cylinders 6 and 7 is exactly 72°. The axis of each of cylinders 4, 5, 6, and 7 makes an angle of exactly 36° with the vertical. Cylinders 4 and 6 are rigidly secured at 50 55

their lower ends to the side $1c$ of member 1 , and cylinders 5 and 7 are similarly secured to side $1d$ of member 1 , it being noted that side $1c$ is perpendicular to the axes of cylinders 4 and 6 , and that side $1d$ is perpendicular to the axes of cylinders 5 and 7 . Hence, it will be seen that a V is formed by the axes of cylinders 4 and 5 , and of cylinders 6 and 7 .

Reciprocally mounted within low pressure cylinder 3 is a piston $3a$ of any conventional type. Operatively connected to piston $3a$ by means of a wrist pin is the connecting rod $3b$. Similarly positioned within high pressure cylinders 4 , 5 , 6 , and 7 are suitable pistons of any conventional type, said pistons being operatively connected to connecting rods by means of wrist pins. In Fig. 1, and to some extent in Fig. 4, the particular arrangement of connecting rods is shown for the correlated cylinders, and particularly in Fig. 1 the correlation between cylinders 4 and 5 is disclosed. The correlation between cylinders 6 and 7 is the same as that between cylinders 4 and 5 . Because of the V arrangement of the cylinders, one of the connecting rods for each of the correlated pairs of cylinders is articulately connected with the other. Hence, as shown in Fig. 1 the connecting rod $4b$ for piston $4a$ is articulately connected with connecting rod $5b$ of piston $5a$ by means of a wrist pin $5c$.

Lying directly beneath and in the axis of cylinder 3 is the crankshaft 9 . Also, said crankshaft is so journaled within the member 1 that it passes through the apex of each V formed by the axes of cylinders 4 and 5 , and cylinders 6 and 7 . The crankshaft 9 is journaled in the above described position within member 1 by means of bearing members $1e$ and rotatably secured thereto by means of removable bearing cap members $1f$, all as seen best in Figures 4 and 1. To the middle of crankshaft 9 and at the crank portion $9a$ is journaled the lower end of connecting rod $3b$ of low pressure piston $3a$ by means of removable connecting rod bearing cap $3c$. On one side of the middle is journaled to crank portion $9b$ the connecting rod $5b$ of the piston for cylinder 5 . At an equal distance on the other side of the middle of crankshaft 9 is journaled to the crank portion $9c$ the connecting rod $7b$ of the piston for cylinder 7 , all as seen best in Figures 1 and 4. Since the piston for cylinder 4 is articulated with the connecting rod for piston of cylinder 5 , and since the piston of cylinder 6 is articulated with the connecting rod for piston of cylinder 7 , and since the piston $3a$ of cylinder 3 is connected with connecting rod $3b$, then as the crankshaft rotates all of said pistons reciprocate, as they are all connected either directly or articulately to crankshaft 9 . Although the travel for piston $3a$ has been shown as equal to that for each of the high pressure cylinders, such an arrangement may be deviated from; that is, the travel for the high pressure pistons may be less than that for the low pressure piston simply by making the throw of the crank portions for each of said pairs of correlated pistons less than the throw of the crank portion for the low pressure piston.

Positioned coaxially on top of low pressure cylinder 3 is a hollow cylindrical shaped member 8 , hereinbefore called the intermediate gas receiver. Said member is seen in Figures 1, 2, 4, 5, and 6, and in detail in Figures 5 and 6. Said member 8 is closed across its bottom end by partition $8a$ shown integral with the cylindrical side of member 8 . Across its top is a circular shaped cover

member $8b$. Positioned within the walls of member 8 , and standing between partition $8a$ and cover $8b$, are four partitions $8c$, said partitions $8c$ extending radially away from the center of member 8 . Extending through the center of member 8 from the under side of its cover $8b$ to partition $8a$ is a tubular portion $8d$. It will be noted that portion $8d$ is integral with $8a$ of member 8 . Connecting with this tubular portion $8d$ are the ends of the four radial partitions $8c$. It will also be noted that the ends of the partitions $8c$ opposite the portion $8d$ are integral with the outside cylindrical wall of member 8 . Hence it will be seen from Fig. 5 that the space within the intermediate gas receiver 8 is divided into four separate compartments by the cylindrical wall of member 8 , by the cover $8b$, by the bottom partition $8a$, by the radial partitions $8c$, and by the tubular portion $8d$. It will be further noted from Figures 5 and 6 that the member 8 is rigidly secured to the compression end of the low pressure cylinder 3 by means of stud bolts $3d$, the lower end of each of said stud bolts being screw threaded within the wall of cylinder 3 , and that the cover $8b$ is rigidly secured to member 8 by the same bolts $3d$. In this manner the partition $8a$ of the intermediate gas receiver 8 serves as a cylinder head for the low pressure cylinder 3 . From Fig. 6 it can be seen that the bore within the tubular portion $8d$ communicates with the cylinder 3 , and further that there is a corresponding hole of slightly reduced diameter in the cover $8b$ that fits over said bore so that the cylinder 3 can communicate with the outside gases; that is, the bore within the member $8d$ and the conforming opening in $8b$ serve as a port. Positioned coaxially within this port, and extending substantially down into said port and for a more or less equal distance above cover $8b$, is a valve guide $8e$, said guide being rigidly secured to the cover member $8b$ by means of lug portions $8f$ on the top side and by lug portions $8g$ on the bottom side, all as shown best in Figures 6 and 8. It will be noted that said lugs $8f$ and $8g$ do not close the port, sufficient space being allowed for gas to pass by, as seen best in Fig. 6. Positioned within valve guide $8e$ is the stem of inlet valve 10 , the valve head seating against the under surface of partition $8a$ and extending into the cylinder 3 from the end of the port $8d$. To keep said valve closed a spring $10a$ is held between a cotter pin $10b$ and the upper lugs $8f$. In this manner a poppet inlet valve is provided for the low pressure cylinder 3 .

Extending downwardly from the under side of cover $8b$ and equidistant from the center of said cover are four studs. Only studs $11a$ and $14a$ show in the drawings, but there is one in each of the four compartments into which the intermediate gas receiver 8 is divided. Each of said studs is rigidly secured by its upper end to cover $8b$. Over the lower ends of each stud are rigidly secured sleeves $11b$, $12b$, $13b$, and $14b$. Each sleeve has an internal bore substantially the diameter of the stud to which it is secured. Within the lower end of the bore of each of the sleeves $11b$, $12b$, $13b$, and $14b$ is reciprocally mounted the upper end of valve stems of valves 11 , 12 , 13 , and 14 . Within each of said bores and between the lower end of each of said studs and the upper end of each of said valve stems is a spring. In Fig. 6 this arrangement is shown in detail for valves 11 and 14 . Valves 12 and 13 though not shown are identical in arrangement. The said springs shown as $11c$ and $14c$ serve to push said valves 11 and 14 respectively against

their respective seats. These valves 11, 12, 13, and 14 seat in their respective ports in the partition member 8a. In Fig. 6 ports 11d and 14d for valves 11 and 14 respectively are shown. Valves 12 and 13 are identical in this arrangement. Fig. 5 shows that there is one of said valves in one each of the four compartments into which the intermediate gas receiver 8 is divided; and it is obvious from Fig. 6 that the valves 11 and 14 through their respective ports 11d and 14d communicate directly with the low pressure cylinder 3. Though not shown, so also do the valves 12 and 13. It will be seen that these valves are arranged to admit gas from the low pressure cylinder 3 and to prevent its escaping back into cylinder 3.

To the high pressure cylinders 4, 5, 6, and 7 are secured the cylinder heads 4d, 5d, 6d, and 7d respectively. Each of said cylinder heads is provided with conventional poppet inlet and exhaust valves. In Fig. 3 the cylinder head for cylinder 4 is shown sectionally as taken along line 3-3 of Fig. 2. In the port 4e is positioned an inlet poppet valve 4f, the head of said valve seating against the inner side of cylinder head 4d. A valve spring 4g is provided to hold valve 4f closed normally. Positioned within the exhaust port 4h is a poppet valve 4i, the head of said valve seating against a reduced portion of port 4h. Positioned within said port 4h is a spring 4j. An externally threaded plug 4k screws into said port and holds said spring between it and the head of the valve 4i so as to normally hold said valve closed. This plug 4k serves also as a valve guide for valve 4i.

Connecting to the inlet port 4e, in any conventional manner, is a tubular conductor 4z. Similarly connecting with each of the other cylinder heads 5d, 6d, and 7d are tubular conductors 5z, 6z, and 7z respectively. Each of said conduits communicates with a different one of the four compartments hereinbefore described into which the intermediate gas receiver 8 is partitioned.

Referring to Fig. 1 the low pressure piston 3a will be seen at the bottom of its intake stroke and just about to begin its compression stroke. The crankshaft 9, as indicated in Fig. 1, rotates clockwise. The crank portion 9b for high pressure pistons 4a and 5a is 108° behind the crank portion 9a for the low pressure piston 3a. The crank portion 9c for high pressure pistons 6a and 7a leads crank portion 9a by 108°. Since the correlated cylinders 4 and 5 are 72° apart in a V arrangement as hereinbefore described, their pistons 4a and 5a will not reach the bottom of their respective strokes simultaneously, but 4a will precede 5a by 72°. Similarly for correlated cylinders 6 and 7, 6a will precede 7a by 72°. By the arrangement shown each piston makes one complete compression stroke and one complete intake stroke for each revolution of crankshaft 9, first the low pressure piston 3a, followed by 4a 72° later, which in turn is followed by 5a 72° later, which in turn is followed by 6a, 72° later, which in turn is followed by 7a 72° later.

The cycle of operation of my gas compressor is as follows: Crankshaft 9 is rotated by any suitable means. Gas is admitted to the low pressure piston 3a on its downward stroke through intake poppet valve 10. On starting the compression stroke of piston 3a, the poppet valve 10, because of the pressure differential and because of spring 10a, closes. The gas within cylinder 3 is then compressed into the four compartments of the intermediate gas receiver 8, poppet valves 11, 12, 13, and 14 being opened by the gas pressure

against the pressure of their respective springs to admit the gas. The total volume of the four compartments is substantially less than the volume of cylinder 3. The poppet valves 11, 12, 13, and 14 are closed by their respective springs when piston 3a reaches the end of its compression stroke. By means of tubular conductors 4z, 5z, 6z, and 7z, each one of the four compartments within intermediate gas receiver 8 communicates with one of the high pressure cylinders 4, 5, 6, 10 and 7.

The gas compressed into each of the said four compartments is retained there, being prevented from escaping back into cylinder 3 by valves 11, 12, 13, and 14, and not being admitted to the high pressure cylinders 4, 5, 6, and 7 for further compression until the respective pistons of said cylinders 4, 5, 6, and 7 have reached the top of their respective strokes. On reaching this point in the cycle of compression, a poppet valve for each of said high pressure cylinders opens due to a pressure differential of gases and against its valve spring to admit gas from gas receiver 8. On reaching the end of the intake stroke and the beginning of the compression stroke, said inlet valve 25 closes by spring action and gas pressure. On reaching a certain predetermined pressure in the compression of the gas in each of the high pressure cylinders an exhaust poppet valve opens, the pressure of the compressed gas acting against the valve spring to open said valve, and the gas is released through said exhaust valve to a gas receiver in any conventional manner (not shown) wherein said gas may be retained for use.

It will be noted that one low pressure cylinder 35 feeds four high pressure cylinders, each of said high pressure cylinders being of substantially smaller diameter than said low pressure cylinder, their ratios of diameters depending upon the degree of compression desired, and that the high 40 pressure cylinders do not reach compression together, but 72° apart in consecutive order, the low pressure cylinder preceding the first of the high pressure cylinders to reach compression by 72°, so that in one revolution of the crankshaft 45 all five cylinders will have reached compression. It will be further noted that all five pistons are driven from one crankshaft.

The foregoing description is of the preferred form of the gas compressor. In Figures 9, 10, 50 and 11 is disclosed a modified form. In this modified form the low pressure cylinder 3, the high pressure cylinders 4, 5, 6, and 7, and the intermediate gas receiver 8, as hereinbefore described, are used. Also the cylinder heads 4d, 5d, 6d, and 7d 55 are used in connection with their respective high pressure cylinders 4, 5, 6, and 7.

The principal difference between the preferred form and the modified form of gas compressor is that in the preferred gas compressor all pistons 60 for both high and low pressure cylinders are driven from one crankshaft and that to accomplish this end the high pressure cylinders are positioned in the hereinbefore described V arrangement, while in the modified form each piston for the various high and low pressure cylinders is driven from a separate and individual crankshaft and that each crankshaft in connection with its respective high pressure cylinders is 65 driven through appropriate gears from the crankshaft for the low pressure cylinder piston and that consequently all cylinders can stand vertically and are grouped about the central low pressure cylinder. In both the preferred form 70

and in the modified form this grouping allows a compact arrangement.

The crankshaft casing and cylinder support member 15 is box shaped as will be seen from Figs. 9 and 10. All the cylinders 3, 4, 5, 6, and 7 are secured at their lower ends in the normally horizontal cover plate 15a and stand vertically with respect thereto. Secured between the cover plate 15a and the bottom plate 15b are the side plates 15c and 15d. The cover plate 15a is secured to bottom plate 15b by bolts 15e.

Lying directly beneath the cylinder 3 and intersecting its axis is a crankshaft 16. This crankshaft is journaled within casing and cylinder support member 15 and extends through said member 15 as shown by dotted outline in Fig. 10, the end 16a extending outside the end of casing 15 connecting with an external source of rotary power. The piston 3a within low pressure cylinder 3 is connected with crankshaft 16 at crank portion 16a by means of connecting rod 3b so as to reciprocate within cylinder 3 with the rotation of said crankshaft 16.

To one end of crankshaft 16 is keyed gear 16b, and to the other gear 16c, as shown in Figs. 9 and 10. Of the same diametral pitch as gear 16b and meshing therewith are gears 17 and 18. Of the same diametral pitch as gear 16c and meshing therewith are gears 19 and 20. All the aforementioned gears 16b, 16c, 17, 18, 19, and 20 are of the same diametral pitch. Gears 17, 18, 19, and 20 are keyed to crankshafts 21, 22, 23, and 24 respectively.

Figure 11 is a sectional view along the line 35 11-11 of Fig. 9 and shows in particular how crankshaft 22 is supported within member 15 hereinbefore described. One end of this crankshaft 22 is journaled within a bore 15g within a boss 15h in a removable end plate 15f. The outer end of said crankshaft 22 is threaded to receive a castle nut 22a and a washer 22b. The nut 22a is pinned to the end of shaft 22 by a cotter pin 22c. Gear 18 is keyed to crankshaft 22 by key 18a. The inner end of shaft 22 is journaled within a bearing post 15i which post 15i is cast integral with bottom plate 15b. A removable bearing cap 15j is provided. Journalled between the crank cheeks 22d of crankshaft 22 is the lower end of connecting rod 5b for piston 5a. Hence as crankshaft 16 rotates crankshaft 22 will also rotate, since the two are geared together by gears 16b and 18. And because gears 16b and 18 have the same diametral pitch the crankshafts 16 and 22 will revolve at the same rate of rotation.

55 The other crankshafts 21, 23, and 24 are supported within member 15 in exactly the same manner as is shaft 22, and the shafts 21, 23, and 24 will turn at the same rate of rotation as will shaft 16 because of gears 17, 19, and 20 as hereinbefore described.

60 The piston 4a is connected with crankshaft 21 by connecting rod 4b; the piston for cylinder 6 is similarly connected with crankshaft 23 and the piston for cylinder 7 similarly connected with crankshaft 24. The throw for each of crankshafts 21, 22, 23, and 24 is exactly the same as is the throw for crankshaft 16. Hence the pistons for cylinders 3, 4, 5, 6, and 7 have exactly the same stroke, the same as in the preferred form of gas compressor.

70 The order of compression is the same in the modified form as in the preferred form.

The mode of operation is the same as in the preferred form except that in the modified form 75 each of the high pressure cylinders is driven from

its respective crankshaft and said crankshafts are geared together to operate as a unit, all as hereinbefore described.

Though I have shown and described a particular construction, combination, and arrangement of parts and portions. I do not wish to be limited to this particular construction, combination, and arrangement, but desire to include in the scope of my invention the construction, combination, and arrangement substantially as set forth 10 in the appended claims.

Having thus described my invention, what I claim as new and desire to secure by Letters Patent is:

1. In a multistage gas compressor, a low pressure cylinder, a piston reciprocally mounted therein, a plurality of high pressure cylinders, pistons reciprocally mounted in each of said high pressure cylinders, a crankshaft operably connected to all of said pistons, a gas receiver intermediate the low pressure cylinder and the high pressure cylinders and operably communicating with said low pressure cylinder, and partitions in said gas receiver dividing said receiver into a plurality of compartments depending upon the number of high pressure cylinders, one each of said compartments operably communicating with one each of said high pressure cylinders.

2. In a multistage gas compressor, a low pressure cylinder, a piston reciprocally mounted therein, a plurality of high pressure cylinders, pistons reciprocally mounted in each of said high pressure cylinders, a crankshaft operably connected to all of said pistons, a gas receiver intermediate the low pressure cylinder and the high pressure cylinders, partitions in said gas receiver dividing said receiver into a plurality of compartments depending upon the number of high pressure cylinders, one each of said compartments operably communicating with one each of said high pressure cylinders, and an inlet valve in each of said compartments, each said inlet valve communicating with the low pressure cylinder.

3. In a multistage gas compressor, a low pressure cylinder, a piston reciprocally mounted therein, a plurality of high pressure cylinders, pistons reciprocally mounted in each of said high pressure cylinders, a crankshaft operably connected to all of said pistons, a gas receiver intermediate the low pressure cylinder and the high pressure cylinders, partitions in said gas receiver dividing said receiver into a plurality of compartments depending upon the number of high pressure cylinders, one each of said compartments operably communicating with one each of said high pressure cylinders and an inlet valve in each of said compartments, each said inlet valve communicating with the low pressure cylinder, and an inlet valve for said low pressure cylinder positioned within said gas receiver, the port thereof extending therethrough and communicating with said low pressure cylinder.

4. In a multistage gas compressor, a low pressure cylinder, a piston reciprocally mounted therein, a plurality of high pressure cylinders, pistons reciprocally mounted in each of said high pressure cylinders, a crankshaft operably connected to all of said pistons, a gas receiver intermediate the low pressure cylinder and the high pressure cylinders, said receiver being secured to said low pressure cylinder and serving as a cylinder head for said low pressure cylinder, partitions in said gas receiver dividing said receiver into a plurality of compartments depending upon the number of high pressure cylinders, one each of

5 said compartments operably communicating with one each of said high pressure cylinders, an inlet valve in each of said compartments, each said inlet valve communicating with the low pressure cylinder, and an inlet valve for said low pressure cylinder positioned within said gas receiver with the port of said valve extending therethrough to the said low pressure cylinder.

6 5. In a gas compressor, the combination of a low pressure compression member, a plurality of high pressure compression members, an intermediate gas holder operably communicating with said low pressure compression member, and partitions within said gas holder dividing said holder into a plurality of compartments, one for each of said high pressure compression members and operably communicating therewith.

7 10. In a gas compressor, the combination of a low pressure compression member, a plurality of high pressure compression members, an intermediate gas holder, partitions within said gas holder dividing said holder into a plurality of compartments, one for each of said high pressure compression members and operably communicating therewith, and an inlet valve in each of said compartments and each of said inlet valves communicating with said low pressure compression member.

8 15. In a gas compressor, the combination of a low pressure compression member, a plurality of high pressure compression members, an intermediate gas holder, partitions within said gas holder dividing said holder into a plurality of compartments, one for each of said high pressure compression members and operably communicating therewith, an inlet valve in each of said compartments and each of said inlet valves communicating with said low pressure compression member, and an inlet valve for said low pressure compression member positioned within said gas holder, the port of said valve extending through

said holder and communicating with the low pressure compression member.

9 20. In a gas compressor, the combination of a low pressure cylinder, a plurality of high pressure cylinders, an intermediate gas holder communicating with said low pressure cylinder, said gas holder being secured to the compression end of said low pressure cylinder and serving as a cylinder head therefor, and partitions within said gas holder dividing said holder into a plurality of compartments, one for each of said high pressure cylinders and operably communicating therewith.

10 25. In a gas compressor, the combination of a low pressure cylinder, a plurality of high pressure cylinders, an intermediate gas holder, said gas holder being secured to the compression end of said low pressure cylinder and serving as a cylinder head therefor, partitions within said gas holder dividing said holder into a plurality of compartments, one for each of said high pressure cylinders and operably communicating therewith, and an inlet valve in each of said compartments and each of said inlet valves communicating with said low pressure cylinder.

11 30. In a gas compressor, the combination of a low pressure cylinder, a plurality of high pressure cylinders, an intermediate gas holder, said gas holder being secured to the compression end of said low pressure cylinder and serving as a cylinder head therefor, partitions within said gas holder dividing said holder into a plurality of compartments, one for each of said high pressure cylinders and operably communicating therewith, an inlet valve in each of said compartments and each of said inlet valves communicating with said low pressure cylinder, and an inlet valve for said low pressure cylinder positioned within said gas holder, the port of said valve extending through said holder to said low pressure cylinder.

35 40. AUBREY C. WHILES.
